UNITED STATES PATENT OFFICE.

PHILIP H. WATSON, OF LEOMINSTER, MASSACHUSETTS, ASSIGNOR TO STANDARD PYROXOLOID CORPORATION, OF LEOMINSTER, MASSACHUSETTS, A CORPORATION OF MASSACHUSETTS.

WATER WAVER.

Application filed August 25, 1926. Serial No. 131,482.

This invention relates to a so-called "water waver" for the hair.

The principal objects of the invention are to provide a construction which will be very easy to manipulate and can be put in the hair by the wearer without any outside assistance and which will produce a wave by being worn in the hair over night; also to provide a construction which will be so light that several of them can be kept in the hair over night without discomfort to the user; and to provide a construction in which the two parts of the water waver can be stamped out of a single blank practically without waste.

Other objects and advantages of the invention will appear hereinafter.

Reference is to be had to the accompanying drawings in which

Fig. 1 is a plan of a water waver in closed position, and illustrating this invention;

Fig. 2 is an edge view;

Fig. 3 is a view showing it as the parts are located when the operator starts to put it in the hair;

Fig. 4 is a view showing the final step in the application of the waver to the hair; and

Fig. 5 is an end view showing the formation of the water wave.

The device comprises two comb-like side pieces 10. These have rather short teeth as compared to a comb, with blunt ends and with the teeth separated widely at the base so that the ends of the teeth of each side piece can be received in the space between the two teeth of the other one. For this reason the two side pieces can be cut out of a single piece of sheet pyroxoline, hard rubber or other material as indicated in Fig. 1. They are shown as held together at their ends by a couple of springs or elastics 11, so that in packing or storing they will occupy the relative positions shown in Fig. 1 and will retain them.

The elastics are covered with cloth to prevent wear and preserve the rubber.

In the use of the device, it is taken in the hands and bent over to the position shown in Fig. 3, or substantially so. It does not come quite to that position because the thumbs of the user come in between the side pieces. In placing it in position the teeth are projected downwardly toward the head. Then it is stretched over to the position shown in Fig. 4, with the side pieces separated, so that there is a space between the

points of the teeth, and put into the hair. Upon letting go of the side pieces the elastics 11 bring them together substantially in a plane and the teeth are projected through a wave of hair as shown in Fig. 5.

This is a very simple manipulation of the device as it does not require any assistance and there is no danger of getting it placed incorrectly. The device is really automatic in operation and not only adjusts itself but enters into the hair by its own action. It has no clasps or metal parts, nothing to adjust or connect and no metal springs. The device cannot fall out of the hair after being put in place as the elastics pull each comb against the other and thereby constantly hold it securely in place. It will hold the hair during sleep without the use of nets or other devices. The size of the wave can be regulated by the amount of stretch given to the rubber in pulling the combs apart. This is so within the control of the user that it can be done even without the aid of a mirror.

Although I have illustrated and described only one form of the invention I am aware of the fact that many changes can be made therein by any person skilled in the art without departing from the scope of the invention as expressed in the claims. Therefore I do not wish to be limited to the exact form shown, but what I do claim is:

1. As an article of manufacture, a water waver for the hair comprising two comb-like side pieces adapted to be placed with their teeth projecting toward each other at a distance apart and having a pair of elastics permanently connecting the ends of both and of such length as to normally force the two pieces together with the teeth of each one extending into the spaces between the teeth of the other.

2. In a water waver, the combination of a pair of side pieces, each having teeth projecting inward toward the other, and a pair of parallel elastics connected to both of their ends in such a way that they can swing about the ends of the elastics as centers and be put into the hair with the teeth pointing down at an angle to each other, and the elastics will then pull them together with the teeth projecting through the hair to form a wave.

In testimony whereof I have hereunto affixed my signature.

PHILIP H. WATSON.
